SNOW RUNNER

Edwin A. Price, 1660 Trenton St., Denver, Colo.

Filed Dec. 28, 1964, Ser. No. 83,169

Term of patent 14 years

(Cl. D34—15)

FIG. 1.

FIG. 2.

FIG. 3.

FIG. 4.

FIG. 5.

FIG. 1 is a perspective view of a snow runner embodying my new design;

FIG. 2 is a side elevation thereof, taken from the side opposite to that shown in FIG. 1;

FIG. 3 is a front elevation thereof;

FIG. 4 is a top plan view thereof; and

FIG. 5 is a side elevation thereof, wherein the seat support includes angular struts.

I claim:

The ornamental design for a snow runner, as shown and described.
